ATTORNEY

UNITED STATES PATENT OFFICE.

CHARLES H. LINDENBERG, OF COLUMBUS, OHIO.

DESIGN FOR A REGALIA-COLLAR.

SPECIFICATION forming part of Design No. 28,717, dated May 24, 1898.

Application filed February 14, 1898. Serial No. 670,328. Term of patent 14 years.

To all whom it may concern:

Be it known that I, CHARLES H. LINDENBERG, a citizen of the United States, residing at Columbus, in the county of Franklin and State of Ohio, have invented and produced a new and original Design for a Regalia-Collar, of which the following is a specification, reference being had to the accompanying drawings, forming part thereof.

Figure 1 is a view, partly in elevation and partly in perspective, of a regalia-collar illustrating my new design; and Fig. 2 is an enlarged sectional view on line xx of Fig. 1.

As shown in the drawings, the leading feature of my design consists in the yoke portion with depending portions having the outline form of links imparted thereto.

a represents the yoke, or that portion of the

collar which passes about the neck of the wearer, the edges of said yoke being ornamented, as indicated at b . On those portions of the collar which depend from the yoke portion a are ornamentations in imitation of interlocking links, increasing in size from the upper to the lower end thereof. The two lower links d are joined by the connected open links e .

Having described my invention, what I claim as new, and desire to secure by Letters Patent, is—

The design for a regalia-collar as herein shown and described.

CHARLES H. LINDENBERG.
